ROBERT D'HURCOURT, (EDOUARD ARMAND,) OF PARIS, FRANCE.

Letters Patent No. 87,130, dated February 23, 1869.

IMPROVEMENT IN APPARATUS FOR PRODUCING HEAT AND LIGHT FROM GASES.

The Schedule referred to in these Letters Patent and making part of the same.

To all whom it may concern:

Be it known that I, ROBERT D'HURCOURT, (EDOUARD ARMAND,) of Paris, in the Empire of France, have invented a new Means for Improving Combustible Gases and Vapors, by mixing them with air or other burning-gases or vapors in a peculiar manner, for the purpose of obtaining a large amount of light therefrom; and I do hereby declare that the following is a full, clear, and exact description thereof, which will enable those skilled in the art to make and use the same, reference being had to the accompanying drawings, forming part of this specification.

The invention consists in an improved means for improving the burning-qualities of hydrocarbon-gases, or fluids, by a mixture of lighting-gas and atmospheric air, in a predetermined proportion and in a peculiar manner, either for obtaining light on special burners, by raising to the red-white heat any un fusible body, a platina corbeil, for instance, or for obtaining heats on heating-apparatus.

This mixture may be made either on the issuing of the gas from the gas-works, or at any other convenient place.

Instead of a mixture of ordinary lighting-gas, a mixture can be formed for the same purpose of any combustible gas and vapors with other burning-gases, such as oxygen pure, deutoxide and protoxide of azote, &c.

Light has been already produced by a mixture of lighting-gas and oxygen or atmospheric gas, made in the apparatus, provided with a burner like to that of Drummont's lamp.

The gas thus provided is especially adapted to burning with a platina corbeil burner, known by the name of Gillard burner, in use for burning hydrogen pure, and, in the present case, used with the mixture which I have mentioned, producing, at the same time, the maximum amount of heat and light, and incomparably more than lighting-gas would produce if mixed with it, and burned in common burners, thereby admitting the use of inferior gases as a base, as any combustible gases will yield an excellent result of light or heat.

The proportion which has proved most convenient for mixture with ordinary coal-gas is, one of gas for two of air, but I do not wish to limit myself to the said proportion.

As the most perfect apparatus may accidentally, or in consequence of mismanagement, happen to work badly, thereby endangering the generation of a detonating-mixture, in such cases the proportion may be reduced to one of gas for seven or eight of atmospheric air.

Figure 1 represents a sectional elevation of one form of apparatus which may be used for forcing the gas;

Figure 2 represents a longitudinal and vertical section of the apparatus which I prefer to use;

Figure 3, a horizontal section of the same;

Figure 4, a partial end and sectional view;

Figure 5, a plan view; and

Figures 6 and 7, sectional and plan views of an apparatus for governing the pressure of the gas being fed into the mixing-apparatus.

Similar letters of reference indicate corresponding parts.

I propose to employ two counters, or meters, one of which has double the capacity of the other, both being in connection with each other by the junction of their axes, so that the one cannot operate independently from the other.

I have the gas conveyed, under pressure, into the little counter only.

The drum in this counter will be set in motion by the pressure of the gas, and carry along with it the drum of the larger counter, the joining on the induction-tube of which is free, which permits of the introduction of the atmospheric air into it.

At each revolution, the small counter will deliver its volume of lighting-gas, and the large one a double volume of atmospheric air.

The gas and air, on issuing each respectively from the counters, will through a conduit, be forced into a chamber common to both, where they become mixed, and thence the mixture will enter the tubes connecting with the burners.

In consequence of this arrangement, the small counter acts like a motor, and the large one like a blowing-engine.

Thus, at each revolution, the little counter will deliver a volume of gas equal to its capacity, and, should any defect or leakage occur, it will deliver more of it, but never less.

As to the large counter, which acts like a pump, or like a blowing-engine, it can deliver at each revolution a volume of air equal to its capacity, but never more; and, should any leakage or other defect occur, it will deliver a lesser volume, of course, and perhaps not deliver any at all.

Since, therefore, in consequence of this arrangement, which consists in sending the lighting-gas alone under pressure, and using the mechanical work produced thereby to exhaust and compress the air and convey it, so that it can be mixed with the issuing gas, the proportion of the lighting-gas, in case of any defect in the apparatus, or of any leakage, can but increase, and that of the atmospheric air can but diminish, and thus will be further and further removed the possibility of having a detonating-mixture.

The burners may, indeed, then work badly, but this will be no danger, and merely a repairable derangement.

I would state that the manometric pressure of about three inches of water, is most convenient for burning a mixture of one of lighting-gas and two of atmospheric air, and the gas, before mixing, should have a pressure theoretically threefold, say of eight inches, and, practically, a pressure forcibly superior, to compensate for friction.

With such pressures, which are to still increase when the mixture is to be conveyed to great distances, medi-

fications in the construction of the ordinary counters would be requisite, which is an easy matter, but would require large diameters.

Other arrangements can be taken, for which the hereinbefore inferences hold good.

An ordinary pump may be taken, like that of a steam-engine, the piston of which will be successively worked up and down by the pressure of the inducted gas.

The inducted and educted gases will be regulated by a slide-valve, like that in steam-engines, or, rather, in webbed dry counters, the effect being produced by the up and down motions of the piston.

This pump will set in motion an ordinary blowing-engine, the capacity of the pump-barrel in the gas-engine and blowing-engine being predetermined, so as to effect the mixture in proper proportion.

Such an arrangement would require tight pistons, and stuffing-boxes with little friction, which it is rather difficult to obtain, chiefly in case of a machine so liable to be neglected.

But the same end may be attained by using, instead of the stuffing-boxes, which allow the passage of the piston-axes, water-joints, like those in use at gas-works, for valves, substituting water for mercury.

There might be substituted for the piston, both for the gas-machine and for the blowing-machine, an iron gas-meter, plunging into a channel filled with mercury, the gas or the atmospheric air coming in successively from above and from beneath.

Or, again, for each chamber, or barrel, there may be substituted two cylindrical vats, A and B, fig. 1 of the accompanying drawings, said vats being connected by flanges provided with a flexible skin, upon which would be fitted a metallic disk, $m\ n$, acting as a piston. The centre of this disk will carry a rod, traversing upward a stuffing-box, as hereinbefore described.

The following is a further arrangement, whereby the stuffing-boxes are altogether avoided.

The apparatus represented in vertical section, (fig. 2,) in horizontal section, (fig. 3,) in end view, (fig. 4,) and in plan, (fig. 5,) consists of a cylinder, $a\ a'\ b\ b'$, with a central partition, $m\ m'$.

This cylinder has two flanges, whereby it is connected to two cylindrical chests, $a\ a'\ e\ e'$ and $b\ b'\ f\ f'$.

Each chest has within it, soldered centrally thereto, another cylindrical chest, k , provided with flanges $r\ r'$.

On each side of the diaphragm $m\ m'$ is a movable cylindrical piece, $s\ u\ s'\ u'$, joined to a sheet-iron circular disk, $t\ t'$, which piece has two flanges, $u\ u'$ and $t\ t'$.

Leathers, suitably stamped and oiled, as for dry counters, connect the flanges $a\ a'$ and $t\ t'$, and likewise the flanges $r\ r'$ and $u\ u'$, so as to form compartments, entirely closed, $G\ G'\ A\ A'$.

The two movable pieces $u\ u'$ and $t\ t'$, fitted on each side of the diaphragm $m\ m'$, carry each of them two arms $x\ x'$, one end of which is attached upon the flange $u\ u'$.

Traversing afterward the cylinders $a\ a'\ e\ e'\ b\ b'\ f\ f'$, through a longitudinal split, they are fixed by their other end on copper tubes $z\ y\ z\ y$, which are moving freely and longitudinally into rings $o\ o'$, fixed on the bottoms of the cylindrical chests $e\ e'\ f\ f'$. By this means, the two chests $u\ u'\ t\ t'$, on each side of the diaphragm $m\ m'$, are connected at an unvariable distance, so that the motion imparted to the one is transmitted to the other, and vice versa.

This being once established, a slide-box, T, is fixed on the upper part of the chest $a\ a'\ b\ b'$.

The gas is admitted from the top, and can, according to the play of the overlap, circulate either at right or at left, and enter either the compartment G or the compartment G' . The play of this slide-valve is the same as for dry counters, so that, when the gas gets into the compartment G' , at right, for instance, it issues at left from the chest G , to return to the slide-box T, and thence escape through the tube S.

The two compartments $A\ A'$ are intended to receive

successively the atmospheric air, and drive it back afterward, for its being mixed, to the lighting-gas issuing through the opening, S.

To this end, on the chest $a\ a'\ b\ b'$, externally, on each side of the diaphragm $m\ m'$, are fitted two small cylindrical boxes $v\ v'$, provided with upper and lower leather slack-valves, both working upward.

Atmospheric air gets in through the lower valve when the suction is produced within one of the chests, and the air goes out through the upper valve when a back compression takes place, so as to encounter, through a tube, R, the gas issuing at S.

The mixture escapes out through C.

It is needless to insist on the means of producing the play of the slide-valve, which play is determined by two rods $j\ j'$, attached to the flange $u\ u'$, and traversing the cylinders $a\ a'\ e\ e'\ b\ b'\ f\ f'$. The to-and-fro motion produced is utilized for working the slide-valve by means of known suitable machinery.

This explanation will suffice to make the work of the apparatus understood.

When the gas is inducted at G', its pressure will push the piece $t\ t'\ u\ u'$, and consequently the other piece, placed opposite to the diaphragm $m\ m'$, since the two pieces are connected invariably by means of the tubes $z\ y$ and $z'\ y'$, when the air contained in the capacity A' is driven back in like manner as the lighting-gas introduced precedently into the capacity G, and, the suction being effected in the capacity A, the atmospheric air gets therein.

At the end of the stroke, the lap of the slide-valve is shifted, and an inverted motion is produced, and so forth.

The capacities of the chambers A and G are determined from the proportions of the mixture.

The necessity of burning at a water-pressure from two and two-fifth to two and four-fifth inches, requires sending the gas at a higher water-pressure, eight inches, which would necessitate the use of a small motor for compressing the gas, which may consist of a pump. Now, the pump which compresses the gas must not, in case the consumption should stop, for example, go beyond a certain degree of pressure which might endanger the apparatus, nor must a vacuum inadvertently be made, in case, for instance, the supply of gas should fail.

For that, I propose the use of the following apparatus, as represented in vertical section, fig. 6, and in plan, fig. 7.

This apparatus consists of two cylindrical chests, A and D, being in communication, and covered with an oiled leather film, or web.

The chest A, or the larger one, receives the gas previous to its entering the compression-pump P.

The web supports a metallic disk, turning round an axis, $m\ n$, and carrying a hook which involves the horizontal rod $a\ b$. When a failing of pressure is produced, in consequence of an insufficiency of gas, at the coming in thereof the disk will be lowered, and carry along therewith the rod $a\ b$.

This rod $a\ b$ traverses a horizontal piece, forming its axis $x\ y$, and carries on its other end a balance-weight, P', which, by means of the rod t, exerts a pressure on the valve s, placed within the chest D. This valve overlaps the end of a conduit leading into the chest D, which conduit receives the gas on its issuing from the force-pump, and communicates with the mixing-apparatus. Should the pressure grow too strong, it will evidently raise the balance-weight P', and then the gas will pass into the chest D, thence to the chest A, and return back again to the pump, thereby neutralizing its action on the mixing-apparatus. If there should be insufficiency of gas coming or inducted, the valve still will be opened, in consequence of the metallic disk of chest A getting lowered. No more gas will then be compressed, nor will there be any inducted.

By means of this apparatus, there would be a certainty to never produce a vacuum, in case the gas should not come in, nor to send an excessive pressure, in case that the consumption should not utilize the whole amount of gas conveyed.

I claim as new, and desire to secure by Letters Patent—

1. The combination, with the sectional cylinder, having the air-chambers A and A', of the apparatus forming the gas-chambers G G', and valve-mechanism T, or its equivalent, substantially as and for the purpose described.

2. The combination, with the same, of the vessels v and v', substantially as and for the purpose described.

3. The combination, with a pump, or other equivalent means of supplying the chambers G and G', of the regulating-apparatus, represented in figs. 6 and 7, substantially as and for the purpose described.
